WILLIAM A. GEIGER, OF CHICAGO, ILLINOIS, ASSIGNOR, BY MESNE ASSIGNMENTS, TO
W. H. MINER, INC., A CORPORATION OF DELAWARE.

ANTIFRICTION BEARING.

Application filed March 24, 1924. Serial No. 701,389.

This invention relates to improvements in anti-friction bearings.

One object of the invention is to provide a simple, practical and relatively inexpensive anti-friction bearing, especially adapted for use as a railway car side bearing, and wherein the parts are so arranged that the anti-friction element proper is automatically returned to center under the influence of gravity when free from load.

Another object of the invention is to provide a bearing of the kind described, wherein the free rolling movement of the anti-friction element proper is permitted, but any accidental bodily shifting thereof resulting from jarring or other causes is substantially prevented.

Other objects and advantages of my invention will more clearly appear from the description and claims hereinafter following.

In the drawing forming a part of this specification, Figure 1 is a vertical sectional view taken through the ends of the body and truck bolsters of a railway car, showing my improvements in connection therewith. And Figure 2 is a vertical sectional view corresponding substantially to the line 2--2 of Figure 1.

In said drawing, 10 denotes the under side of the body bolster and 11 the upper side of the corresponding opposed truck bolster. The improved side bearing is shown as applied to the truck bolster and comprises, broadly: a base casting, retaining member or housing A; an anti-friction element proper B; and counterweights C—C, at the ends of said anti-friction element.

The housing A is of more or less box-like form, having end walls 13—13 and vertical side walls 14—14, each of the latter having a laterally outwardly offset portion 15 for a purpose hereinafter described. A plate 12 is arranged in the bottom of the housing to form a bearing surface for the anti-friction element, said plate being secured to the truck bolster by means of rivets 19 and secured to the housing by means of rivets 16. A pair of ribs 17 are formed at the opposite ends of the housing, the ribs at each end extending inwardly of the housing toward those on the opposite end and having their inner edges curved to provide stops or abutments for limiting the rolling movement of the anti-friction member. Open-

ings 18 may be provided through the side walls of the housing at their lower ends, above the wear plate 12, to facilitate the removal of dirt, cinders or other foreign matter from the housing.

The anti-friction element B, as shown, is in the form of a truly cylindrical roller adapted to roll back and forth to either side of central position on the bearing plate 12. This roller is provided with a main or central portion 20 and with projections or lugs 21 at the bottoms of the opposite ends. The projections 21 have an arcuate lower or under face conforming to the periphery of the roller, the top faces of said projections being flat or plane, as shown at 22.

The counterweights C—C are arranged at opposite sides of the anti-friction element, one of said counterweights being arranged in each of the offset portions 15, these offset portions forming vertical guideways, said guideways being closed at their upper ends by webs or flanges 23, and open at their lower ends. Each counterweight C is preferably in the form of a rectangular member, whose width is slightly less than the width between the opposed vertical walls forming the guideway 15, thus permitting vertical movement of the counterweight in the guideway without undue friction therebetween and preventing any rotation or undue shifting of the counterweight therein. The width of each lug 21 is substantially equal to the width of each counterweight C; that is, it is substantially equal to the width of the guideway 15, so that when the roller is in its normal central position, as shown in full lines in Figure 1, any accidental bodily shifting thereof resulting from jarring or other causes is substantially prevented. The counterweights have their lower straight edges or surfaces resting on the straight upper faces 22 of the lugs 21 of the anti-friction element so as to be supported thereby.

As the roller is actuated in either direction from its normal position, under load and after the body bolster 10 has come into contact with the roller, the anti-friction element proper will roll on the wear plate 12 to an end position as indicated in dotted lines in Figure 1, thereby causing the lugs 21 to tilt and thus slidably engage the counterweights and lift them to their uppermost position. As soon as the load on the element B is re-

6 moved, the weight of the counterweights acts on the upturned ends of the lugs to roll the roller back and serves to effectively return the anti-friction element to its normal central position.

10 The use of the counterweights and projections on the anti-friction element proper in the manner disclosed, brings about a very efficient and sensitive return effect upon the anti-friction element and one which allows a more compact structure than obtainable were counterweights of equal effect employed rigidly with the anti-friction element. It will be noted that, as the projections 21 are moved 15 from the full line position to the dotted line position shown in Figure 1, the centers of mass of the counterweights C are elevated a much greater distance than are the centers of mass of the projections 21, this being due to 20 the fact that the rising edges of the projections 21 act as cams in lifting the counterweights while the latter are confined to vertical movement. Furthermore, during the return action when the load is removed from 25 the anti-friction element proper, the full weight of the counterweights C is effective with the same degree of efficiency throughout the entire return movement of the anti-friction element and until the last instant of the 30 return action, when the counterweights and projections 21 come into full surface contact, it being evident that the counterweights bear upon edges of the projections 21 until the last instant of the return action.

35 As previously pointed out, the width of the lugs and counterweights are only slightly less than the width of the guideways, thereby permitting the rocking or rolling of the anti-friction element in either direction and yet preventing any shifting of the element which might disturb the relation of the parts and prevent the return of the element to normal central position after its actuation.

40 In assembling the device, the counterweights are inserted into the guideways, the anti-friction element is next arranged within the housing with its lugs positioned in the guideways, and then the wear plate 12 is secured to the housing by means of the rivets.

50 16. After the bearing has been assembled in this manner, it may be shipped or handled without danger of the parts becoming lost, stolen, damaged or misplaced.

55 I have herein shown and described what I now consider the preferred manner of carrying out my invention, but the same is merely illustrative and I contemplate all changes and modifications that come within the scope of the claims appended hereto.

60 I claim:

1. In an anti-friction bearing, the combination with a housing adapted to be mounted on a bolster or the like; of an anti-friction element proper disposed within said housing and adapted to roll to either side of normal

central position therein, said element having segmental projections normally arranged at the bottom of said sides, said housing being provided with vertical guideways of a width substantially equal to the width of said segmental projections and permitting but slight play therebetween lengthwise of said housing; and vertically shiftable counterweights slidably arranged within said guideways and constantly supported on said segmental projections so as to be slidably engaged and lifted thereby when said element is actuated to either side of central position.

2. In an anti-friction bearing, the combination with a housing adapted to be mounted on a bolster or the like; of an anti-friction roller disposed within said housing and adapted to roll to either side of central position therein, said element having segmental projections at the bottom of its sides, each of said segmental projections having a flat top face, and a rounded lower face conforming to the periphery of said roller; and vertically shiftable counterweights having flat bottom faces supported on the flat top faces of said segmental projections, said housing being provided with vertical guideways for slidably receiving said counterweights and said projections, the width of said segmental projections and said counterweights being substantially equal to the width of said guideways.

3. In an anti-friction bearing, the combination with a housing adapted to be mounted on a bolster or the like; of an anti-friction element arranged within the housing and adapted to roll to either side of central position therein and having eccentric projections located at the sides of the element and adjacent the periphery of said element, each of said projections having an inwardly disposed flat engaging face; and vertically shiftable imperforate counterweights having peripheral edges slidably engageable with the flat engaging faces of said projections, said housing having vertical guideways adjacent said counterweights so as to receive the same and constrain the counterweights to vertical movement whereby movement of said element to either side of central position effects slidable engagement of said projections and said counterweights to displace the latter in said guideways to cause an unbalanced condition serving to return said element to a central position when the actuating pressure is removed therefrom.

4. In an anti-friction bearing, the combination with a housing having a bottom opening, said housing being adapted to be mounted on a bolster or the like; of a detachable bearing plate for closing said bottom opening, an anti-friction roller disposed in said housing and adapted to roll on said bearing plate to either side of normal cen-

tral position with respect thereto, said element having an integral eccentric projection at each end thereof, and said housing being provided with elongated vertical 5 guide-ways closed at their outer extremities by overhanging portions of said housing, said element being insertable in said housing through said bottom opening; and counter-weights arranged in said guide-ways and 10 having portions resting on said projections, and adapted to be vertically displaced thereby upon movement of said element, movement of said counter-weights being limited by the overhanging portions of said housing, and said counter-weights and said overhanging portions serving to maintain said 15 anti-friction element against detachment with respect to said housing.

5. In an anti-friction bearing, the combination with a housing having side and end 20

walls, said side walls being off-set to provide vertically extending centrally disposed guide-ways of restricted width as compared with the longitudinal extent of said housing; a bearing surface, an anti-friction element having a diameter greater in extent than the height of said housing, and the width of said vertical guide-ways; eccentric projections on said element adjacent the periphery thereof, said projections being of a 25 width as to fit within said vertical guide-ways having flat top faces; and counter-weights arranged in said guide-ways and having peripheral flat edges thereof resting on said flat faces of said eccentric projections. 30

In witness that I claim the foregoing I have hereunto subscribed my name this 19th day of March 1924.

WILLIAM A. GEIGER.
